IMPULSE MECHANISM

Judson O'D Shepherd, Atlanta, Ga.

Application May 16, 1941, Serial No. 393,745

16 Claims. (Cl. 179—90)

This invention relates to pulse regenerators particularly useful in telephone systems where the length and condition of a line may introduce distortion in signaling pulses of a character which must be accurately timed.

The object of the invention is to produce a simple and economical device which will store information conveyed in the shape of trains of pulses and which will retransmit such information on demand by regenerating like trains of pulses.

A feature of the invention is a means responsive to trains of pulses for translating each train into a code, displacing a plurality of displaceable members in accordance with such code and advancing before another plurality of such displaceable members for each said train of pulses. By way of example, the code may be a permutation code and where the trains of pulses are to consist of one to ten pulses each such permutation code may have four places. Hence for each train of pulses to be registered or recorded a set of four displaceable members is provided which may be displaced in any combination of such four places.

Thus a series of trains of impulses may be registered by successively displacing the members of a like number of sets of displaceable members. By displaceable member is here meant anything whose position or condition may be changed. As illustrated a displaceable member is a mechanically movable electric switch but it is to be understood that the term is not to be limited by this showing but is to be given a wider connotation.

Later, at a time determined in any one of a variety of ways, a detecting means will be associated with the various sets of displaceable members in order and will translate the code there found into trains of pulses identical in number with the trains of pulses used for recording the information. The outgoing pulses will be regenerated, particularly in the sense that they will be of full strength and accurately timed.

Thus when a pulse regenerator of the type herein disclosed is employed it is possible to signal over longer lines and lines in poorer condition than heretofore. Moreover a time element may be introduced between the recording of the information and the transmission of the information so recorded which may be useful.

A feature of the invention is a means for recording the digits of a telephone designation or like information on a series of sets of mechanically operable electric switches which may later

be tested by a detecting means. Each set of such switches represents one digit and these sets of switches may be rapidly operated one after the other or there may be long and uneven intervals between the operation of one set and a succeeding set. Since the information is recorded by mechanical displacement the record may be preserved as long as desired without adding to the maintenance charges as for battery drain where relays are operated and locked up or other means where electrical marking is employed. Such a device lends itself particularly well to uses where the information is recorded piecemeal.

Another feature of the invention is a translator in the form of a device which may be set in any one of a number of positions each corresponding to a particular number of pulses in a train and which in any of said positions will set up a corresponding code. This latter operation consists by way of example in operating a plurality of common members equal in number to the number of places in the code used. Thus a transitory record of an incoming train of impulses is made which may be selectively transferred to a particular set of displaceable elements for what may be termed a permanent record.

Another feature of the invention is a selector which designates the particular set of displaceable elements to be operated and which acts as a link between the said common elements operated by the translator and the selected set on which a record is to be made.

Another feature is a restoring device operated by the said selector which restores to normal all displaced elements of a set just prior to its use for registering a new record.

Thus a record may be mechanically recorded and such record maintained even after it is used and until a new record is made—the old record only being wiped out in the process of making the new record.

The translator may consist of a mechanical device which may be rotated or otherwise moved to a selected position or it may consist of a circuit arrangement consisting of a plurality of magnets one for each place in the code and which are energized in code so as to operate the common members on which the transitory record is made.

The device in its broad form is capable of a variety of uses. In one form it may be used in a line as a simple pulse regenerator to receive incoming trains of pulses and to regenerate and transmit like trains of outgoing pulses. The

outgoing pulses may be arranged to closely follow the incoming pulses or they may be delayed in any one of several known ways. In other words the regeneration and transmission of outgoing pulses may wait upon the operation of a start control circuit.

The device may be used in what is known as a key pulsing circuit, that is, the incoming trains of pulses or their equivalent may be taken from local key sets or the original translation may be dispensed with and the code common elements may be directly set by keys.

Again the device may be used for call indicator work. In this connection the record may be written on the sets of displaceable elements by mechanical movement of such elements in code and this record through appropriate circuit arrangements may be used to set the well-known call indicators.

Other features and uses will appear in the following description.

The drawings consist of five sheets containing thirteen figures as follows:

Fig. 1 is a side view of the mechanism;

Fig. 2 is a bottom view looking upward;

Fig. 3 is an end view partly in cross section taken as indicated by the line 3, 3 in Fig. 2;

Fig. 4 is a detailed side view illustrating how the code switches are operated and released;

Fig. 5 is a fragmentary detailed bottom view taken on the line 5, 5 in Fig. 1 illustrating how the outpulse sending mechanism is prevented from overtaking the impulse registering means.

Fig. 6 is a fragmentary view partly in section, taken on the line 6, 6 in Fig. 2 illustrating the operation of the impulse magnet;

Fig. 7 is a fragmentary side view showing the switch actuating cam of the device and the digit registering arm in counter-clockwise movement illustrating the manner in which the switches are actuated when the cam sector has been moved and the manner in which the switch fails to become actuated when the corresponding cam sector has not been moved;

Fig. 8 is a view similar to that of Fig. 7 showing the position of the parts when the movement illustrated in Fig. 7 has been completed but before the actuated cam sectors have been returned to normal;

Fig. 9 is a view similar to that of Fig. 8 showing the positions of the parts after the cam sectors have been returned to normal and the apparatus is ready to record the next digit;

Fig. 10 is a diagram illustrating the plan of the cutting of the cam sector drum actuated by the incoming impulse circuit;

Fig. 11 is a circuit showing how the apparatus of Figs. 1 to 9 is operated to regenerate impulses;

Fig. 12 is a circuit diagram alternative to that part of the circuit of Fig. 11 to the right of the line X, X showing how the cam sectors may be operated by individual magnets rather than by a cam sector drum; and

Fig. 13 is a circuit diagram showing how the apparatus may be used to transmit impulses after having been set by manually operated keys rather than by incoming trains of impulses.

The device consists of a frame on which and to which various members are mounted and secured. As illustrated, the device is capable of recording ten digits of a telephone number or ten items of any other information in code. The device has no normal position though as shown in Fig. 1 it is set to record on the number 1 set

5 of switches. Where the device is arranged to start the sending of outpulses as soon as the first registration has been completed then the number of sets of switches may be reduced even below the number of items to be recorded as, for instance, five sets of switches may be amply sufficient to use for seven digit telephone numbers, the exact number depending only on the ability of the subscriber to dial faster than the apparatus can transmit outpulses.

10 Where the device is arranged for delayed starting so that the transmission of outpulses will not begin for an indefinite period after all items of information have been recorded then there must be at least as many sets of switches as the maximum number of items to be recorded. The ten sets shown herein are by way of example and these as shown are numbered 1 to 10 in Fig. 1. These are secured in a semi-circular frame piece 11. As illustrated in Fig. 2, each set of switches consists of five separate switches, each comprising a plurality of blades, which are here numbered 12 to 21, inclusive. The blades 12, 15, 17, 19 and 21 are grounded here on the frame 11 or in any other approved manner. The blades 14, 16, 18 and 20 are normally insulated from the frame and from their companion blades. The parts 22 and 23 represent other members of the frame and on the member 22 there is mounted a shaft or bearing member 24 carrying four metallic pieces 25, 26, 27 and 28 which are rotatable. The piece 25 as may be seen from Fig. 1 may be rotated in a clockwise direction and when so rotated will jam between the ends of the blades 14 and 15 and thereby ground the blade 14 and any electric circuit connected thereto. While the contact pieces 25 to 28, inclusive, are rotatable on the shaft 24, they are mounted in such a way that friction will hold them in any position to which they have been moved. As an alternative or supplement to providing friction mountings for pieces 25, the grounded blade, such as 15, of each pair may be extended beyond its companion blade so as to frictionally engage said 20 pieces to assure the circuit between the blades being maintained open unless purposely closed. Thus, in Fig. 1 the part 25 as shown in its normal position has been moved to this position in a manner to be hereinafter described and limited 25 in such movement by a stop pin 29. In Fig. 7 the piece 25 is shown during its clockwise movement after it has left its normal position and just before it has made electrical contact with the spring 14. In Fig. 8 the piece 25 is shown jammed between the contact springs 14 and 15. 30 At a point which may be defined as the center of the semicircular lines of the frame 11, bearings in the frame members 22 and 23 are provided and in these bearings a shaft 30 is mounted. On this shaft there is also mounted a device 31 which may be termed a digit registering arm. This arm is rotatable in a counter-clockwise direction as viewed in Fig. 1 through a ratchet wheel 32 impelled by the magnet 33. The ratchet wheel 32 is provided with twenty teeth and the digit registering arm 31 has duplicate equipment at either end whereby half a revolution of the digit registering arm 31 will perform a complete operation of the ten sets of switches. The digit registering arm 31 carries a pair of shafts or bearings 34 and 35, on each of which are mounted for cam actuated pallets such as 36. As seen in Fig. 2, the cam actuated pallets 36 to 39, inclusive, are mounted on the shaft 34 and the pallets 40 to 43, inclusive, are mounted 35

on the shaft 35. The pallets 36, 37, 38 and 39 and the pallets 40, 41, 42 and 43 operate the electrical contact pieces 25, 26, 27 and 28 respectively under conditions to be described. As shown in Fig. 1, the digit registering arm 31 is in position awaiting the proper operations for registering a digit. The digit registering arm 31 also carries at its extremities two bars 44 and 45 which act to restore any of the parts, such as 25, to normal. Thus, in Fig. 1 it will be noted that the bar 44 is poised in such a position that upon the next counter-clockwise movement of the digit registering arm 31, the bar 44 will come into physical contact with any operated switch parts, such as 25 associated with the number 2 set of switches and restore them to normal. Thus, in a manner to be fully described hereinafter, upon the registration of the first digit, the arm 31 will move one step in a counter-clockwise direction whereupon the switches of number 2 set will be restored to normal in preparation for the registration of another digit thereon.

As indicated in Fig. 1 and shown in Fig. 2, the extremities of the digit registering arm 31 have cam surfaces formed thereon which cooperate with the fifth set of terminals of each set. Thus, with the arm 31 in the position shown in Fig. 1, the normal contact between the spring 12 and the spring 13 is broken as indicated in Fig. 5. As will appear hereinafter during the discussion of the circuit diagram the fifth set of contacts 12 and 13 in Fig. 2 will actually be associated with the four code contacts of the first set. Thus, the operated set shown in Fig. 5 indicated as being physically associated with the No. 2 set in Fig. 1 is electrically associated with the No. 1 set shown in Fig. 1. This is for the purpose of preventing access of the pulse transmitting apparatus to a set of switches until registration has been made thereon. That is, the registration has been made on the tenth set and the digit registering arm 31 has been moved to the position shown awaiting registration on the first set of switches.

The means by which the various switches may be operated is controlled as follows: As may be seen in Fig. 3, a frame piece 46 secured to the frame piece 22 is provided for mounting a shaft 47 which carries what may be termed a code drum 48. This code drum is a cylindrical piece secured to the shaft 47 and having cam faced cuttings for the operation of the code sectors 49 to 52 inclusive. Also secured to the shaft 47 is a ratchet wheel 53 which is impelled through the movement of the armature 54 of the magnet 55. The magnet 55 will respond separately to the incoming impulses of a train of impulses and thus cause the drum to move to a position corresponding to the number of pulses in the train. In accordance with the position to which the digit drum has been moved, the cam sectors 49 to 52, inclusive, will be operated in various combinations. Thus, as indicated by the chart, Fig. 10, in which the shaded portions represent cam surfaces with those in lines along A, B, C and D corresponding to cam sectors 49, 50, 51 and 52 respectively, if the code drum has been moved one step then the cam sector 49 will be operated. And, by way of example, if the cam drum 48 has been moved six steps cam sectors 50 and 51 will be operated. That is, cam sectors 49 to 52 are mounted on the shaft 30 and are normally held in an extreme position in a counter-clockwise direction as seen in Fig. 4, for example, by appropriately mounted springs. Each 75

such cam sector has an arm 56 which bears on the face of the cam drum 48. If the drum 48 is in position 1 then the cam sector 49 as indicated in Figs. 4, 7 and 8 will be rotated a short distance in a clockwise direction through the arm 56 riding up on a raised portion of the cam drum 48. Thereafter, if the arm 31 is moved in a counter-clockwise direction one step, the pallet 36 will ride up on the face of the cam provided on the cam sector 49 just ahead of the pallet and engages with blade 25 of the first set of contacts in such a manner that the springs 14 and 15 will be connected together to ground spring 14. This operation will be clearly understood from the drawings, Figs. 4, 7, and 8, where the sequence of the movement of the pallet 36 may be seen. In Fig. 8 the digit registering arm 31 has been moved in line with the third set of contacts where it is awaiting further movement for the registration of information on the second set of contacts, as is plainly indicated. In this figure the code sector arm 49 is indicated as being still in its operated position and the code sector 50 is indicated as being in its normal position. In Fig. 9 all of the code sectors have been returned to normal. In this connection it should be noted that a set of contacts 57 and 58 operated by a finger 59 cooperating with the off-normal bar on the code drum 48 are shown operated in Figs. 7 and 8 and restored to normal in Fig. 9. These contacts and the operating arrangements therefor are for the purpose of controlling the restoration to normal of the code drum after the registration of each digit or item of information.

In the operation of the device, the code drum is rotated by a train of pulses, the registration thereof being effected by operation of a corresponding combination of switch blades through cooperation of the several pallets with the cam faces of the actuated code sectors incident to advancement of arm 31, and the code drum is restored to normal. This is repeated for each succeeding train of pulses. In this manner, then, the various sets of contacts provided for digits 1 to 10, inclusive, may be operated and it will be recognized that with four switches in each set, a four place permutation code may be used. The information thus recorded may be stored indefinitely and then taken off through appropriate means at any desired time. As indicated in the circuit diagram, Fig. 11, this storage period is at a minimum since the taking off of the information will proceed immediately upon the first step of the digit registering arm 31, but it will be recognized that electrical control may be provided to delay the start of the outpulsing circuit to any other desired time. Since many start control means are known, no other specific means will be illustrated.

The mode of operation of this device when used as a pulse regenerator may be seen from the circuit diagram in Fig. 11. Here a line is represented by conductors 60 and 61 extending from a dial 62 to a relay 63. This showing is schematic and represents a condition established after the line has been taken into use and the dial 62 is ready to be operated. The relay 63 will be operated as soon as the line is seized and through its armature and front contact closes an obvious circuit for the slow-releasing relay 64. A series of impulses are then sent by the dial 62 and each impulse results in a momentary deenergization of the relay 63. The slow-releasing relay 64 remains operated so that a series of impulses

are now sent from ground armature and back contact of relay 63, front contact and armature 5 of slow-releasing relay 64 through the windings of slow-releasing relay 65 through the winding of the code drum magnet 55 to battery. The code drum magnet 55 responds separately to each impulse and in a manner hereinbefore described rotates the code drum 48 through the ratchet wheel 53. The movement of the ratchet wheel 53 occurs upon the energization of the magnet 55. The slow-releasing relay 65 responds to the series of impulses as a whole and, therefore, the magnet 33 responds to the series of impulses as a whole also. As soon as the code drum is caused to take one step, the circuit through the off-normal contacts 57 and 58, is closed for a purpose which will be hereinafter described. The magnet 33, upon energization, prepares to impel the digit registering arm 31 forward but this does not occur until after the full series of impulses has been registered through the operation of the code drum magnet 55 and the slow-releasing relay 65 becomes deenergized through the steady attraction of the armature of relay 63. When relay 65 deenergizes, then magnet 33 deenergizes and impels the digit registering arm 31 forward whereupon the switches of the first set are actuated. When the magnet 33 becomes completely deenergized a circuit is established from ground, the armature and back contact of slow-releasing relay 65 through the off-normal contacts 57 and 58 through the armature and back contact of magnet 33 through the back contact and armature of magnet 55, through the winding of magnet 55 to battery and ground. In this manner the code drum magnet is put in a self-interrupting circuit so that it will step the code drum around automatically until the normal position is reached, whereupon the off-normal contacts 57 and 58 open the circuit.

The operation of relay 64 completed a circuit for the operation of relay 73 through the upper armature and back contact of relay 72. Upon the movement of the digit registering arm 31 to the position in line with the third set of switches the springs 12 and 13 physically associated with the second set of switches but electrically associated with the first set of switches are closed together and, therefore, wiper 66 is grounded. Wipers 66 to 70 belong to a switch for controlling the output circuit and are moved by the stepping magnet 71 upon its deenergization. The wipers 66 to 70, inclusive, are shown in association with the first set of code switches. When wiper 66 is grounded as a signal that the first set of switches has been set, then a circuit is established to the winding of relay 72 whereupon this relay becomes energized to open the circuit to the winding of relay 73, which will release after an interval depending on the value of resistance 83 and condenser 84 as will be hereinafter described. A circuit will then be established from the interrupter 81 through armature 3 and front contact of relay 64, armature and back contact of relay 73, front contact and lower armature of relay 72, winding of relay 74 to battery. Relay 74 is known as the out-pulse relay and will attempt to open the outgoing line passing through its armature 2 and back contact and the armature 2 and front contact of relay 64 in accordance with the interrupter 81. This interrupter being machine-driven will create out-pulses accurate in their timing. However, the opening of the outpulse circuit by armature 2

of relay 74 is without effect at this time as this armature and its contact are shunted by the back contact and armature 2 of relay 75. Therefore, the outpulse circuit remains closed.

Upon each operation of relay 74 a circuit is closed from ground through armature 1 and front contact of relay 74 to the winding of sequence switch magnet 76. This magnet controls a number of sequence switch cams 71 to 80, inclusive, which are closed in the positions indicated in the conventional manner. The sequence switch is advanced one position upon each release of magnet 76. There are twelve positions of this sequence switch of which the normal one is number eleven. It then passes through positions 12, 1, 2, 3 and so forth until it again reaches its eleventh position.

Now assuming that the digit one has been registered, then in accordance with the chart, Fig. 10, the wiper 67 will be grounded through its associated bank contact by virtue of the circuit from blade 15 to blade 14 being closed. By the same token no one of the wipers 68, 69 or 70 will be grounded.

Upon the first energization and release of relay 74 after the interrupter 81 has been connected thereto by relay 72 the sequence switch will be driven to position 12 whereupon relay 75 will be energized through the contacts cooperating with cam 79. Relay 75 locks through its lower winding and its armature 3 to ground now on cam 79 in its 12th position. Relay 75 opens the circuit through its armature 2 and allows relay 74 to have control of the outpulsing circuit.

Upon the next closure of interrupter 81 relay 74 operates and thereby transmits one properly timed impulse into the outpulse circuit. At the same time the magnet 76 is energized to advance the sequence switch to position 1 at the conclusion of the impulse. In this position the energizing circuits for relay 75 are opened and this relay becomes deenergized to stop the outpulsing.

It should be noted that upon the energization of relay 75 the stepping magnet 71 is energized through armature 1 and front contact of relay 75. Upon the release of relay 75, magnet 71 is released so that the wipers 66 to 70, inclusive, are advanced to their next positions. The magnet 76 is now included in a self-interrupting circuit through cam 80 and the back contact and armature 1 of relay 75 so that the sequence switch returns to normal automatically. It should be noted that relay 73 is slow to release by virtue of a resistance 83 and a condenser 84 connected to its winding. Thus when relay 72 first opens the circuit of relay 73 it will release after a predetermined time and close the circuit from the interrupter 81 to relay 74 to cause the movement of the sequence switch to position 12. Thereafter relay 73 is energized through armature 4 of relay 75 until the complete train of outpulses has been sent, whereupon it is again released but due to its slow-releasing characteristics holds the impulse circuit to relay 74 open until the sequence switch has had ample opportunity to return to normal.

During the energization of relays 73 and 75 a substitute circuit for relay 74 may be traced through armature 5 of relay 75 and the lower armature of relay 72.

Through the sequence switch cams being arranged as indicated the relay 75 will remain operated through positions 12 and 1 for the digit 2, through positions 12, 1 and 2 for the digit 3,

through positions 12, 1, 2 and 3 for the digit 4 and so forth.

Upon the movement of the wipers 66 to 70, the next digit is transmitted after a predetermined interval controlled by the release of relay 73, and this action continues automatically until an open contact is overtaken by wiper 66 whereupon transmission is halted. If this is caused by the action of the outpulse transmitting circuit operating faster than the impulses are registered then this halt in transmission is only temporary but if it is caused by completion of transmission of all digits to be handled, the mechanism will rest for the duration of the call.

The device will remain where left at the completion of a call and upon being used for a subsequent call, will register the trains of received impulses on the code switches beginning at the corresponding position. That is, the arm 31 need not be restored to the position shown in Fig. 1 before handling a call.

In the event a call is abandoned after a portion of the digits have been dialed or all have not been transmitted, the resulting release of relay 63 and thereafter relay 64 will cause the circuit from interrupter 81 to be opened and another circuit closed from the back contact of the armature of magnet 71, armature 1 and back contact of relay 64, wiper 66 to ground at switch contacts 13, thus causing magnet 71 to operate and release repeatedly until the wipers 67 to 70 are associated with the code switches one position back of arm 31, where they will be available to handle a new call. This position will be marked by the movement of wiper 66 to such a position that an open circuit is encountered.

A variation of the invention is shown in Fig. 12 where the circuit arrangement to the right of the line $x-x$ may be substituted for that part of the circuit arrangement of Fig. 11 to the right of the line $x-x$. In this case instead of having a magnet 53 to operate the code drum there is a minor switch stepping magnet 85. The code drum will be eliminated and four magnets used to operate the code sectors 49 to 52, inclusive. It will be readily understood how these code sectors can be moved by the magnets. Magnets 89 to 92, inclusive, are provided to operate the code sectors 49 to 52, inclusive, respectively. The minor switch stepping magnet 85 will step the wipers 66 and 87 around to a point corresponding to the incoming train of impulses and the magnets 89 to 92 will accordingly be operated in certain code combinations. During the sending of a train of impulses the slow-releasing relay 65 will be operated and will respond to the train of impulses as a whole. The magnet 85 will respond to each impulse separately. During the operation of relay 65 a slow-releasing relay 88 will be operated by relay 65 and in parallel therewith a slow-releasing relay 93 will be operated to control the operation of the digit registering arm magnet 33. At the end of the train of impulses relay 65 will release and close a circuit through the upper armature and front contact of relay 88 to the wipers 66 and 87 to operate the code sector magnets 89 to 92. The circuit for relay 93 will also be opened but this being slow-releasing will not allow the magnet 33 to release and, therefore, to advance the digit registering arm 31 until the magnets 89 to 92 have been properly energized. Relay 93 is timed to release prior to the release of relay 88. At an appropriate interval after the circuit through the upper armature of relay 88 has been closed this relay will release and there-

upon close a circuit through its lower armature and back contact through the off-normal contacts 94 and 95 to the winding of magnet 66 which releases the wipers 86 and 87 of the switch to their normal position. The remaining operations of the device with this variation are the same as hereinbefore described and are believed to be readily understood.

Fig. 13 shows a manner in which this device 10 may be used for key pulsing circuits, that is, the device may be set by the depression of keys, let us say, at an operator's position rather than through the registration of incoming trains of impulses. Thus, the keys marked 1 to 0, inclusive, may be 15 used to register telephone numbers on a device like that herein described. If the digit 1 is to be registered the key marked 1 will be operated and the relay 101 will be energized through its upper winding and the winding of relay 111. This relay becomes operated and causes the energization 20 of the digit registering arm magnet 33. This magnet in turn closes a circuit to complete a locking circuit for the lower winding of relay 101. Relay 64 is operated by an obvious circuit closed by 25 contacts 112 which may be manually operated or be a part of a relay in an associated circuit, not shown, it being sufficient for these purposes that said contacts be closed while a call is being handled. The relay 101 will close an appropriate 30 circuit to operate one of the magnets 89 to 92, inclusive. This condition will be maintained until the key 1 has been released. As soon as the key has been released then relay 111 will be released and this in turn will allow the magnet 33 to move 35 the digit registering arm 31 to its next position. The operation of the device will be as rapid as it is possible for an operator to manipulate the keys 1 to 0 and, therefore, the registration of a number will proceed simultaneously with the operation of the keys. This registered number will 40 be transmitted in the manner set out above with respect to Fig. 11.

It is to be recognized that in adapting this device to key pulsing the code sectors may be directly set in combinations by keys connected thereto through suitable linkage in which case magnet 33 will be arranged to be operated upon each actuation of the keys.

It will be recognized that this device is capable 50 of many other uses and adaptations within the capacity of one skilled in the art. The device would be particularly useful for call indicator working where the four-element switches could act not only as a storage means but as a translating means for translating trains of dial impulses into the well-known four-place call indicator code. By the provision of any well-known start control circuit the device would act as a storage means to hold a plurality of digits indefinitely until a call indicator becomes available.

It is intended that this specification will cover all such modifications of this device which come within the spirit of the invention and the scope of the following claims.

65 What is claimed is:

1. A device comprising a plurality of individual sets of mechanically displaceable elements on which information may be recorded in code, a common set of mechanically displaceable elements, a means responsive to incoming information in a first code, a translator responsive to said means for operating said common mechanically displaceable elements according to a second code, a selector for designating one of said 70 individual sets of mechanically displaceable ele-

ments and means operated thereby for transferring a record established on said common to said individual mechanically displaceable elements.

2. A pulse regenerator comprising a step-by-step member responsive to pulses of incoming trains of digital pulses, a set of common code indicators operable by said step-by-step member, a plurality of sets of displaceable elements, a means responsive to trains of pulses for associating said common code indicators with a different set of displaceable elements for each said train of pulses, means for transferring the record established on said common code indicators to the displaceable elements of the said associated set, and means for generating and transmitting outgoing digital pulses controlled by said displaceable elements.

3. A pulse regenerator comprising a plurality of individual sets of mechanically displaceable elements, each said set comprising four of said elements arranged to be operated in a four-element permutation code, a step-by-step cam surfaced element responsive to the separate pulses of a train of digital pulses, a set of common cam discs operated by said cam surfaced element, a means responsive to trains of pulses for associating said common cam discs with a different set of said mechanically displaceable elements for each train of pulses for transferring the combination set up on said common cam discs to an individual set of mechanically displaceable elements, and means for generating and transmitting outgoing digital pulses controlled by said individual mechanically displaceable elements.

4. A pulse regenerator comprising a plurality of individual sets of mechanically displaceable elements, each said set comprising four of said elements arranged to be operated in a four-element permutation code, a step-by-step cam surfaced element responsive to the separate pulses of a train of digital pulses, a set of common cam discs operated by said cam surfaced element, a means responsive to trains of pulses for associating said common cam discs with a different set of said mechanically displaceable elements for each train of pulses for transferring the combination set up on said common cam discs to an individual set of mechanically displaceable elements, and means for signaling controlled by said individual mechanically displaceable elements.

5. A device comprising a plurality of sets of mechanically displaceable elements, each said set being operated to record information in code thereon, a common set of displaceable element operating members, means for associating said common means with each said set of displaceable elements, restoring means operated by said last means for restoring all displaced elements of a set as said associating means moves into position to associate said common means with said set of displaceable elements, and a signaling circuit controlled by said sets of displaceable elements.

6. A device comprising a plurality of sets of mechanically displaceable elements, each said set being operated to record information in code thereon, a common set of displaceable element operating members, a step-by-step means responsive to incoming digital pulses for operating said common members, means for associating said common means with each said set of displaceable elements, restoring means operated by said last means for restoring all displaced elements of a set as said associating means moves into position

to associate said common means with said set of displaceable elements and a signaling circuit controlled by said sets of displaceable elements.

7. A device comprising a plurality of sets of mechanically displaceable elements, each said set being operated to record information in code thereon, a common set of displaceable element operating members, a set of electromagnets equal in number to the number of displaceable element operating members for operating said members, means for associating said common means with each said set of displaceable elements, restoring means operated by said last means for restoring all displaced elements of a set as said associating means moves into position to associate said common means with said set of displaceable elements and a signaling circuit controlled by said sets of displaceable elements.

8. A device comprising a plurality of sets of electrical switches, each said set being operated to record information in code thereon, each said switch comprising a stationary terminal and a freely movable blade, a common set of switch blade moving members, a step-by-step means responsive to incoming digital pulses for operating said common members, means for associating said common members with each said set of switch blades, restoring means operated by said last means for restoring all operated switch blades of a set as said associating means moves into position to associate said common members with said set of switch blades and a signaling circuit controlled by said sets of electrical switches.

9. A device comprising a plurality of sets of electrical switches, each said set being operated to record information in code thereon, each said switch comprising a stationary terminal and a freely movable blade, a set of discs each having thereon a camming surface for each said set of electrical switches, each said disc having a normal position in which said camming surfaces are displaced from an operative position with respect to said switches, a set of operating members each of which will upon movement operate a corresponding switch when the corresponding disc is moved from its normal position, means for selectively operating said camming discs, means for thereupon moving said operating members for transferring the record set up on said camming discs to a set of said switches, means for simultaneously restoring to normal any operated blades of the next succeeding set to be used, and a signaling circuit controlled by said sets of electrical switches.

10. A device comprising a plurality of sets of mechanically displaceable elements, a cam plate for each element of a set and common to said sets of said elements, a cam surface on each of said plates for each of said sets of elements, means for selectively moving said cam plates, each said cam plate having a normal and an operated position, a set selecting arm, an actuator for each cam plate carried by said selecting arm, each said actuator being arranged upon movement of said arm to ride over the corresponding cam surface of its associated actuator and to engage and displace one of said elements responsive to its said associated cam plate being in its operated position.

11. A register device including a row of mechanically displaceable elements in order, an actuator common to said elements, means for advancing the actuator along said elements, a cam plate, means to move said cam plate from a normal to an operated position and cam surfaces on

said cam plate corresponding respectively to each element and adapted to move by cam action said actuator transversely to its direction of travel as it is advanced to cause it to engage and displace said elements if said cam plate has been moved to its operated position and not to engage said elements if said cam plate is in its normal position whereby said elements may be selectively operated under control of said cam plate moving means.

12. The method of regenerating electrical impulses received in trains over an incoming circuit which consists in translating each of said trains into a permutation code corresponding to the number of impulses therein, momentarily registering each of said codes in a common register, mechanically transferring each of said registrations to registers individual to each train and subsequent to the latter operation decoding the registration in the individual registers into trains of impulses in an outgoing circuit with each of the latter trains corresponding to an incoming train.

13. A device comprising a plurality of sets of mechanically displaceable elements, each said set being operated to record information in code thereon, a common set of displaceable element operating members, a set of electromagnets equal in number to the number of displaceable element operating members for operating said members, a distributing switch responsive to incoming impulses for selectively operating said electromagnets, means for associating said common means with each said set of displaceable elements, restoring means operated by said last means for restoring all displaced elements of a set as said associating means moves into position to associate said common means with said set of displaceable elements and a signaling circuit permanently associated with and controlled by said sets of displaceable elements.

14. A device comprising a plurality of sets of mechanically displaceable elements, each said set being operated to record information in code thereon, a set of common members one for each element in said sets for preparing said sets for operation, a step-by-step means responsive to incoming digital pulses for selectively operating said members, means responsive to trains of said incoming digital pulses for designating a set of displaceable elements for operation and a set of links carried by said designating means for translating the selectively operated condition of said members to the set of displaceable elements with

which said designating means is at the time associated, restoring means carried by said designating means operative upon the movement thereof into association with a said set of displaceable elements for restoring all displaced elements of said set to normal and a signaling circuit permanently associated with and controlled by said sets of displaceable elements.

15. A device comprising a plurality of sets of mechanically displaceable elements, each said set being operated to record information in code thereon, a set of common members equal in number to the number of elements in each of said sets, means responsive to trains of incoming digital impulses comprising means responsive to the separated pulses of said trains for selectively operating said members and a selector arm responsive to said trains each as a whole, a set of links carried by said selector arm operative upon and during the movement of said selector arm from association with one to association with another of said sets of displaceable elements for translating the selected operation of said members into a corresponding selected operation of the elements of that set of displaceable elements with which said arm was operatively associated during the reception of a train of pulses, and a signaling circuit permanently associated with and controlled by said sets of displaceable elements.

16. A device comprising a plurality of sets of electrical switches, each said set being operated to record information in code thereon, each said switch comprising a stationary terminal and a freely moving blade, a common set of switch blade moving members, a step-by-step means responsive to incoming digital pulses for operating said common members, said means comprising a drum having a cam surface responsive to the impulses of a train, a set of camming discs equal in number to the number of said switches in a set and each having a normal and an operated position and being operated to and from said positions by the selective positioning of said cam drum and a selector arm for operatively associating said set of switch blade moving members with one of said sets of electrical switches, a restoring means carried by said selector arm for restoring all operated switch blades of a set upon the movement of said arm into cooperative association therewith, and a signaling circuit permanently associated with and controlled by said electrical switches.

JUDSON O'D SHEPHERD.
